UNITED STATES PATENT OFFICE.

WILLIAM F. PERSONS, OF CLEVELAND, OHIO, ASSIGNOR TO THE GUIDE MOTOR LAMP MANUFACTURING COMPANY, OF CLEVELAND, OHIO, A CORPORATION OF OHIO.

SIDE LAMP FOR AUTOMOBILES.

Application filed May 31, 1923. Serial No. 642,444.

To all whom it may concern:

Be it known that I, WILLIAM F. PERSONS, a citizen of the United States, residing at Cleveland, in the county of Cuyahoga and State of Ohio, have invented a certain new and useful Improvement in Side Lamps for Automobiles, of which the following is a full, clear, and exact description, reference being had to the accompanying drawings.

10 This invention relates generally to automobile lamps and more particularly to lamps known as side lamps and usually arranged upon the cowl of the automobile.

The object of the invention is to provide a simple and highly efficient means for securing the glass and retaining ring or door to the casing and another object is to so construct such means that they may be quickly and easily released whenever it is desired to replace the glass or the electric bulb.

Another object is to so construct such fastening means that they will not detract from the attractiveness or ornamentation of the 25 design of the lamp as a whole.

With these various objects in view, the invention consists in the details of construction of the various parts and in the manner of combining or arranging the same all of 30 which will be fully described hereinafter and set forth in the appended claims.

In the drawings forming a part of this specification, Fig. 1 is a vertical sectional view of a lamp embodying one form of my invention; Fig. 2 is a face view of the same, Fig. 3 is a detail view of the securing ring, Fig. 4 is a fragmentary sectional view taken on the line 4-4 of Fig. 1 and Figs. 5 and 6 are similar views of slight modifications.

In carrying out my invention, I employ a lamp casing A which is substantially cylindrical in shape and at its front open end is formed with an offset or shoulder flange 45 B which forms the seat for the edges of the lens or glass C, which lens or glass is preferably made translucent either in the composition of the glass or by grinding or sand blasting. For the purpose of holding the 50 lens or glass firmly seated I employ a channeled ring frame or door D of sheet metal, the inner forward edge D' of which contacts with or engages the front face of the glass or lens adjacent the edges thereof and 55 the rear edge D² of said channeled ring or

frame extends beyond the shouldered edge of the lamp casing A and is inclined or tapered towards the cylindrical body portion of said casing as most clearly shown in Fig. 1 and between the exterior of the lamp 60 casing and the interior of the rear portion of the channeled ring or frame is interposed a divided spring ring E which serves as a wedge and securely holds the frame or door in position upon the casing and against the glass, said ring resting against the shouldered front of the casing and the contracted or tapering portion of the frame.

The ends of the ring are turned outwardly as indicated at E' and provided with 70 small knobs or handles E² and at the bottom of the ring or frame the rear portion thereof is cut away as indicated at D³ in order that the ends E' may project there-through, said ends engaging the edge D⁴ of 75 said cut-out portion as is most clearly shown in Figs. 1 and 4. When the ring is thus expanded it securely unites the ring and casing inasmuch as it wedges these parts securely together. When the spring ring is 80 contracted by bringing the knobs or handles together, its circumference is materially reduced and likewise its diameter and the ring or frame can then be quickly and easily removed from the lamp casing for the purpose of replacing the electric bulb or replacing the glass in the front of the casing.

In assembling the parts, the spring ring is first placed around the casing just at the rear of the flanged or shouldered front thereof, the glass is then placed in the ring or frame and then the shouldered front of the casing is placed within the ring or frame or the ring or frame is placed over the shouldered front of the casing and the ends of the spring ring are then brought towards each other and inserted in the cut-out portion D³ and permitted to spring into engagement with the ends thereof. The casing, glass, frame and spring clamping ring are thus securely connected together.

In the form shown in Fig. 5 the frame D is cut out at D⁵ and D⁶ in such a manner that a wedge shaped part D⁷ is formed between the cut portions D⁵ and D⁶. The extensions E' of the ring E extend through the openings D⁵ and D⁶.

When the ring E is contracted by bringing the knobs E² together the extensions E' will ride on the faces D⁸ of the wedge D⁷,

and ring will be forced rearwardly out of engagement with the lamp housing A and frame D.

Fig. 6 shows cam slots D⁹, used in place of the parts D⁵ to D⁸ described above, which will act in the same manner as the form just described. The slots D⁹ are enlarged at D¹⁰ for convenience in assembling.

It will thus be seen that I provide a simple and highly efficient form of side light equal of carrying out all of the objects of the invention hereinbefore referred to.

Having thus described my invention, what I claim is:—

15. 1. The combination with a lamp casing having a shouldered front edge, of a glass seating upon said shouldered edge, a channeled ring or frame surrounding the shouldered edge of the casing, the forward inner edge of said ring or frame contacting with the front face of the glass, the rear edge of said ring or frame being inclined toward the casing, and a divided spring ring interposed between the shouldered edge of the
20. casing and the inclined or contracted edge of the ring or frame, said spring ring having outwardly projecting end portions each passing thru an opening or notch produced
- 25.

in the rear edge of the ring or frame, an edge portion of the opening or notch being so formed that the spring ring is forced rearwardly thereby when its end portions are drawn toward each other.

2. The combination with a lamp casing having a shouldered front edge, of a glass seating upon said shouldered edge, a channeled ring or frame surrounding the shouldered front edge of the casing, the forward inner edge of said ring or frame contacting with the exterior of the glass, the rear edge 40 of said ring or frame extending rearwardly beyond the shouldered edge of the casing and inclined toward the casing and a divided spring ring interposed between the shouldered edge of the casing and the rearwardly 45 extending inclined edge of the ring or frame, the ends of said ring projecting radially outwardly through an opening in the ring frame, said opening extending rearwardly whereby when the end portions of the spring 50 ring are drawn together said portions will be caused to move rearwardly.

In testimony whereof, I hereunto affix my signature.

WILLIAM F. PERSONS.
